HONING DEVICE

George Frederick Wagstaff, Cheltenham, England, assignor to Delapena & Son Limited, Cheltenham, England

Application October 4, 1948, Serial No. 52,703
In Great Britain October 6, 1947

5 Claims. (Cl. 51—184.1)

1

This invention relates to honing devices, that is to devices used for finishing components where a superlative finish is required and/or where the diameters have to be held to very fine limits. It is concerned with honing devices employed for finishing external surfaces of revolution, for example the surfaces of pins, plug gauges or the like, and referred to herein as "external hones."

The invention has for its object to provide a new or improved construction of external hone which is simple and economical in production and the use of which will ensure accuracy of the work produced, particularly as regards the removal of any trace of ovality which may have been left, for example, by the previous grinding or fine machining operation.

According to one aspect of the invention an external hone comprises guide means adapted to bear against the surface of revolution of the work at at least three points, and an abrasive element adapted to be brought to bear against said surface of revolution at a point substantially diametrically opposite one of said points.

In accordance with another aspect of the invention the external hone comprises an abrasive element arranged to bear against the surface of revolution of the work at a point substantially diametrically opposite one of a plurality of guide members and a movable support to hold the work between said plurality of guide members.

In certain constructions of external hone according to the invention some or all of said guide means or members may also take the form of abrasive elements but normally they will merely comprise members so arranged as to provide guiding and bearing surfaces for the work as it rotates relatively to the hone.

Three embodiments of the invention will now be described, by way of example, with reference to the accompanying drawings, in which:

Figure 1 is a front elevation of an external hone according to the invention, a portion of one of the jaws being broken away to show the movable support.

Figure 2 is an end elevation of the hone illustrated in Figure 1.

Figure 3 is a front elevation of a modification of the hone illustrated in Figure 1, showing a different arrangement of the screw and nut mechanism and movable support, and

Figure 4 is a similar view of a further modification of the hone, illustrating a different arrangement of the abrasive element and movable support.

Referring to Figures 1 and 2, the hone com-

prises a body 10 which may be held in the hand around the work while the latter is rotated or which may be mounted in the jaws of a chuck and rotated while the work is held stationary.

5 The body consists mainly of two jaws 11, 12, reduced at one end to form hinge members 11a, 12a which receive a hinge pin 13 by which the jaws are pivoted together, the latter being of bowed form so that with their free ends 11b, 12b more or less close together, a substantially circular aperture 14 is defined between the jaws to accept the work. The upper jaw 11 is formed at a point intermediate its ends with an inwardly disposed slot 15 to receive a block 16 which projects into the aperture 14 and is bifurcated to form a pair of guide members 17, 17a disposed in V relation to each other. The guide block 16 is rigidly retained in its slot in the jaw by means of a set screw 18.

20 A movable support in the form of a pawl-like member 19 is pivotally mounted at one of its ends to the free end 12b of the lower jaw 12 by means of a pivot pin 20, the jaw being gapped to receive such end of the pawl-like member.

25 The other end or nose 19a of the latter projects into the aperture 14 at a point such that, with the work projecting into the aperture (as indicated in broken lines), the guide members 17, 17a lie on one side of a diameter of the work

30 parallel to a chord drawn through the points of contact of the guide members 17, 17a with the work while the nose 19a of the pawl-like member lies on the other side. As illustrated, the pawl-like member is arranged so that the guide members 17, 17a are disposed substantially symmetri-

35 cally with respect to the nose 19a of the pawl-like member and, due to the fact that the guide members are relatively fixed and arranged at an angle to each other, they define a constant outwardly narrowing throat in which the work is held by the nose of the pawl-like member.

30 The jaw 12 carries an inwardly projecting abrasive element 21 secured in a holder 22 which is fixedly mounted in a slot 23 formed in the jaw by means of a set screw 24.

The abrasive element 21 is arranged at a point diametrically opposite the guide member 17 of the bifurcated block. A headed screw 25 passes through a clearance hole in a trunnion block 26

50 pivotally mounted in the free end 11b of the jaw 11, which is gapped to receive the screw, the point of the latter passing through a clearance hole in the pawl-like member 19 and threading into a trunnion block 27 pivotally mounted therein. Thereby tightening of the screw 25 first

draws the nose 19a of the pawl-like member inwardly of the aperture 14 between the jaws until it bears upon the surface of the work and holds the latter between the guide members 17, 17a. Thereafter continued tightening of the screw 25 draws the free end 12b of the lower jaw 12 to which the pawl-like member 19 is pivoted towards the free end 11b of the upper jaw 11, with the pawl-like member acting as a lever and its nose 19a the fulcrum, until the abrasive element 21 is brought to bear against the surface of the work.

With this arrangement the abrasive element 21 is mounted in the lower jaw 12 so that its distance from the screw trunnion block 27 is greater than that of the nose 19a of the pawl-like member. Thereby, due to the increased leverage, upon tightening the screw 25 the abrasive element 21 will always bear harder on the surface of the work than will the nose 19a of the pawl-like member. This is of importance as it enables the operator to get the "feel" of the cut which the abrasive element is putting upon the work. In order to maintain the jaws 11, 12 and pawl-like member 19 against collapse a compression coil spring 28 is disposed around the screw 25 with its ends abutting the trunnion blocks 26, 27.

Figure 3 illustrates an alternative arrangement of the screw and nut mechanism and the pawl-like member. The upper and lower jaws 29, 30 are hingedly mounted on a pivot pin 31, as in the previous construction, and the guide block 32 and abrasive element 33 are also similarly positioned. A headed screw 34 mounted in trunnion blocks 35, 36 connects the free ends 29a, 30a of the upper and lower jaws in order to permit adjustment of the degree of opening and closing of the latter. A pawl-like member 37 is pivotally mounted between lugs 38 which protrude inwardly from the free end 29a of the upper jaw so that the pawl-like member projects into the aperture 39 between the jaws, the nose 37a of the pawl-like member being arranged to bear on the surface of the work on the opposite side of a diameter of the latter parallel to a chord drawn through the points of contact between the work and the guide portions of the bifurcated guide block 32 from such guide portions and being disposed so that such guide portions are substantially symmetrical with respect thereto. Adjustment of the pawl-like member 37 is effected by a second headed screw 40 which passes through a clearance hole 41 in the upper jaw 29 and threads into a trunnion block 42 pivotally mounted in the pawl-like member. To provide a bearing for the head of the screw 40 a boss 43 is formed on the exterior surface of the upper jaw. As in the previous construction springs 44 are provided to prevent the jaws 29, 30 and the pawl-like member 37 from collapsing inwardly.

Figure 4 shows a further embodiment of the invention. In this construction the upper and lower jaws 45, 46 are hingedly mounted on a pivot pin 47, which also forms the hinge point for the pawl-like member 48. A bifurcated guide block 49, symmetrically disposed in relation to the nose 48a of the pawl-like member, which is arranged on the opposite side of the diameter of the work, parallel to the guide block chord, from the guide portions of the guide block, as already described is secured to the upper jaw 45. The abrasive element 50 is carried by the lower jaw 46 and in this construction is disposed outwardly of the nose 48a of the pawl-like member relatively to the pivot pin 47. Opening and clos-

ing of the jaws 45, 46 is effected by the headed screw 51, whilst a second screw 52 is provided to draw the nose 48a of the pawl-like member on to the surface of the work.

5 I claim:

1. An external hone comprising in combination a body including two jaws pivoted together towards one end for relative angular movement to define a variable aperture therebetween and having spaced guide surfaces adapted to bear unyieldingly at angularly spaced points against a surface of revolution of work placed within said aperture, a support pivoted to said body and capable of being swung in the plane of the jaws 10 about its pivot towards said guide surfaces to hold the work thereagainst, an abrasive element carried by said body and arranged to bear unyieldingly against said surface of revolution, means tending to resiliently hold the other end 15 of said jaws open and said support away from said guide surfaces, and screw means operable to overcome said resilient means to bring the jaws and support to, and positively hold them against outward movement from, any one of an infinite 20 number of relative positions of adjustment.

2. An external hone comprising in combination a body including two jaws pivoted together and arranged to provide an aperture therebetween, said body having guide surfaces adapted 30 to bear at a plurality of circumferentially spaced points against a surface of revolution of work placed within the aperture, an abrasive element carried by said body and adapted to bear unyieldingly against said surface of revolution at 35 a point substantially diametrically opposite one of said plurality of points, means for drawing the jaws towards each other and setting them positively against outward movement in the relative positions to which they have been adjusted 40 to effect adjustment of the abrasive element relatively to said surface of revolution, and a support movable with respect to the body to hold the work between said guide surfaces, the movement of said support being effected by the same 45 means as those by which the jaws are drawn towards each other.

3. An external hone comprising in combination a body including two jaws pivoted together and arranged to provide an aperture therebetween, said body having guide surfaces adapted 50 to bear at a plurality of circumferentially spaced points against a surface of revolution of work placed within the aperture, an abrasive element carried by said body and adapted to bear unyieldingly against said surface of revolution at 55 a point substantially diametrically opposite one of said plurality of points, screw and nut mechanism for drawing the jaws towards each other and setting them positively against outward 60 movement in the relative positions to which they have been adjusted to effect adjustment of the abrasive element relatively to said surface of revolution, a compression coil spring disposed around said screw to maintain the jaws against 65 collapse, and a support movable with respect to the body to hold the work against said guide surfaces.

4. An external hone comprising in combination a body having an aperture therein, a bifurcated block carried by said body and projecting inwardly into said aperture so that guide portions of said block bear at two circumferentially spaced points against a surface of revolution of work placed within the aperture, an abrasive element carried by said body and arranged 75 to

project into said aperture and bear against said surface of revolution at a point substantially diametrically opposite one of said guide portions, a pawl-like member pivotally mounted on said body and which projects into the aperture and is capable of being swung in the plane of the body about the pivot so that a nose portion of the pawl-like member is brought into contact with said surface of revolution to hold the work against the two guide portions which are disposed substantially symmetrically with respect to said nose portion, and means carried by the body for adjusting said abrasive element relatively to said surface of revolution.

5. An external hone comprising in combination a body including two jaws pivoted together and arranged to provide an aperture therebetween, said body having guide surfaces adapted to bear at a plurality of circumferentially spaced points against a surface of revolution of work placed within the aperture, an abrasive element carried by said body and adapted to bear unyieldingly against said surface of revolution at a point substantially diametrically opposite one of said plurality of points, screw and nut mechanism for drawing the jaws towards each other and setting them positively against outward movement in the relative positions to which they have been adjusted, a pawl-like member pivoted

to one of said jaws and movable with respect to the body to hold the work between said guide surfaces, the nut of the screw and nut mechanism being pivotally carried by said pawl-like member and the arrangement being such that tightening of the screw first causes a nose portion of said pawl-like member to bear upon said surface of revolution and then draws the free end of the jaw carrying the pawl-like member towards the free end of the other jaw, with said pawl-like member acting as a lever and said nose portion as a fulcrum, until said abrasive element is brought to bear against said surface of revolution.
